UNITED STATES PATENT OFFICE

2,330,777

COPYHOLDER

Edward L. Elliott, Woodside Park, Md., assignor
to Federal Business Machines Corporation,
Washington, D. C., a corporation of Delaware

Original application November 20, 1940, Serial No.
366,463. Divided and this application November
23, 1942, Serial No. 466,632

8 Claims. (Cl. 24—66)

This invention relates to copy holders for successively exhibiting lines of text with reference to a guide, and it comprises more particularly the construction which accommodates copy of various widths and secures it in a position for accurate alignment of the text with the guide.

The present application is a division of my prior, co-pending application Serial No. 366,463, filed November 20, 1940.

Although copy holders may be employed for a variety of uses incidental to the preparation of written text material, they are most extensively employed in conjunction with the ordinary typewriter and as an adjunct to type setting machinery. In either case, the copyist is confronted with succeeding sheets of copy material which are likely to be of differing widths. As a consequence, successive copying operations may involve substantial changes in the requirements of the copy holder from the standpoint of the size of copy to be supported and retained.

Most commercial copy holders now in use will only accommodate copy of a width either equal to or less than the width of the copy supporting panel. Thus, if it is necessary to copy text from a sheet or sheets which are wider than the supporting panel of the copy holder, those margins of the sheets which extend beyond the holder are unsupported. This results not only in a failure of initial alignment, but the edges of the retained sheet are blown and unsteadyed by air currents as well as distorted by curling, which is normal to thin paper.

Misalignment of any portion of the copy will necessarily result in inaccurate designation by the line guide thereby increasing the likelihood of error in copying and reducing the efficiency of the copy holder to such an extent that its use for wide copy is hardly feasible.

Although some attempts have been made to provide for the support of copy wider than the supporting panel of the copy holding device, these have been characterized by failure to provide apparatus whereby rapid and accurate location of the papers is possible consistent with firm support during any normal copying operation.

It is therefore an object achieved by this invention to provide a copy holder which is adjustable to accommodate sheets of copy of a wide variety of sizes and at the same time to permit quick and accurate positioning of the sheet to align its text with the copy holder guide.

Other objects and advantages of this invention will be apparent from the following description and drawings wherein:

Figure 1 is a front view of the copy holder, showing the copy holding panel in extended position in dotted lines.

Figure 2 is a fragmentary front view of a modified form of the invention adapted for support of copy not wider than the panel of the holder.

Figure 3 is a vertical sectional view taken along the line 3—3 of Figure 1.

Figure 4 is a vertical sectional view taken along the line 4—4 of Figure 1.

Figure 5 is a perspective view of the copy clamping means.

Figure 6 is a perspective view of the supporting bars for a wide line guide.

Figure 7 is a perspective view of the wide line guide normally mounted on the bars shown in Figure 6.

Figure 8 is a perspective view of the supporting bar for the wide copy grippers.

Figure 9 is a perspective view of one of the grippers used on the bar shown in Figure 8.

Referring more particularly to the drawings:

The copy holder shown consists of a base 10, a vertical standard or guide 11 attached thereto, and a copy supporting member 12 slidably mounted for telescoping movement on standard 11. The standard 11 is formed with guides 13 along the opposite vertical edges thereof and with a top flange 14 of a depth substantially equal to that of the guides 13. The copy supporting member 12 consists of a front plate which is slightly wider than the standard 11 formed with vertical side flanges which embrace the guides 13. A top wall 16 extends rearwardly of the copy support 12 and is co-extensive with the side flanges.

A copy gripping device is attached to supporting member 12 and serves to hold sheets of paper or other copy thereon. This device comprises primarily a flat bar 17 extending for the full width of the copy support 12 and a pair of L-shaped flat strips 18, one shank of each of which extends upwardly from either end of flat bar 17 while the other shank extends rearwardly across the top 16 of supporting member 12 in a plane at right angles to the plane of bar 17. Strips 18, at their ends remote from bar 17, are connected by a barrel 19 which includes two downwardly projecting tabs 20. Each tab 20 is attached by spot welding or in other suitable manner to a leaf spring 21 which in turn is secured to the rear face of copy supporting member 12, at 22. The springs 21 are normally under such tension that they tend to hold the bar 17 firmly against the front face of copy supporting member 12.

It will be readily understood that in constructing

the copy gripper device bar 17, strips 18, barrel 19 and tabs 20 may be stamped from a single blank and may thereafter be bent into the form shown in Figure 5. The flat surface of bar 17 which faces the copy support 12 has a continuous strip of resilient gripping material 23 such as sponge rubber affixed to it. A thumb rest 24 is attached to the center of top wall 16 of the member 12. In the construction shown in Figure 2 the barrel 19 has detachably received therein one arm of a U-bar 25. U-bar 25 is mounted for pivotal movement about barrel 19 as an axis, the free arm thereof extending rearwardly of the back wall 15.

When copy is to be held on the supporting member 12 in reading position, the operator may grasp barrel 19 and thumb rest 24 with his fingers and press them toward one another. This will result in compression of springs 21 and the forward movement of strips 18 and bar 17 carried thereby. Thus, bar 17 will be moved away from the face of the support 12. Once gripping strip 23 and front face of the support 12 are spaced sufficiently for apart to accommodate a sheet or sheets of copy therebetween, such copy is inserted and an edge thereof is pushed up until it comes to rest against the lower surfaces of the shanks of strips 18 which are at right angles to the long axis of the plate 12 and hence to the paper held thereagainst. These shanks of strips 18 serve to align the paper on the supporting member 12 for the reason that they lie in a plane parallel to its top 16. Once the paper is in position, thumb grip 24 and barrel 19 are released. Springs 21 then move to normal position as shown in Figures 3 and 4 thereby compressing the sheet or sheets of copy between gripping strip 23 and the front face of the supporting plate 12. Since gripping strip 23 is continuous for the full length of bar 17, the copy will be held firmly in aligned position during the ordinary manipulation of the copy holder.

If material is to be copied from a sheet of a bound volume, such as a stenographer's notebook, the top edge of bar 17 is used as a sight line to align the copy while pages not in use may be thrown back over the top 16 and held by the free arm of U-member 25. Since U-member 25 is mounted for pivotal movement in barrel 19, the distance of the free arm thereof from the back of support 12 may be adjusted to accommodate any number of pages up to a cumulative thickness equal to the length of the radial arm of the U-member.

Inasmuch as the material to be copied is held between the gripping strip 23 and the face of the copy supporting member 12, it will hang downwardly parallel to the front face of the support. In order to designate a particular line to be read, a line designating guide 26 is ordinarily employed. Guide 26 is mounted to extend across the face of the support in spaced relation with respect thereto. It consists of a flat strip formed with a barrel 27 along one of its long edges. One shank of a U-bar 28 is mounted in this barrel while the other shank is pivotally mounted in a similar barrel 29 attached to the rear face of the standard 11. When copy is being attached to the copy support and it is desired to have line designating guide 26 out of the way, U-bar 28 is moved about its axis in barrel 29 until the radial arm thereof is substantially at right angles to the long axis of the copy support. This will leave ample space between

the face of the support and the line designating guide to permit easy adjustment of the paper in the manner heretofore described.

When material is being supported for movement past line designating guide 26 it is normally held solely by the clamping bar 17. It will be noted that this bar is co-extensive with the supporting panel 12. Normally this panel will be of a width to accommodate at least ordinary paper, i. e. eight and a half inches. According to this invention, however, it is possible to support copy of a width considerably in excess of normal. To this end the wide line designating guide and wide copy holder shown in Figures 1, 3, 4, 8 and 9 are employed. As has been stated, line designating guide 26 is mounted on a U-shaped bar 28, one shank of the U-bar being inserted in a barrel 27 provided on the line guide while the other shank extends into barrel 29 attached to the standard 11. When lines of copy of a width in excess of the width of the copy holder are to be placed in the machine, the shank of U-bar 28, located in the barrel of line designating guide 26, is separated therefrom and the projecting end of a wide line designating guide 26' is passed therewith. In this instance the shank of U-bar 28 is supplanted by a pair of oppositely extending U-bars 28', the ends of which enter the barrels 27' and 29 respectively. The separate U-bars so employed are shown in Figure 6.

While it is evident by consideration of Figure 2 that bar 17 would serve at least to a certain extent to align and hold copy on the support panel 12, it is also evident that when the copy is of a width such that it extends considerably beyond the panel 12 on either side, the edges of the copy not held by bar 17 will not maintain their aligned position, since the paper will not be sufficiently stiff to maintain its upper edge on a straight line. The action of gravity as well as the action of air currents will normally cause the free ends of the copy to fall below the horizontal plane designated by the lower surfaces of horizontal shanks of strips 18 which serve as aligning means. To overcome this difficulty, heretofore considered insuperable, a bar 30 having copy grippers 31 therein is employed. Bar 30 is used in substitution for U-member 25 (Figure 2) which is removed from barrel 19 for the purpose. One of the shanks of bar 30 is then inserted in barrel 19 until the end of the other shank can be aligned and inserted in the opening at the other end of the barrel 19. Bar 30 is then aligned as shown in Figure 1. Copy grippers 31 are each provided with a barrel 32 for slidable mounting of the grippers on rod 30 thereby to accommodate copy of any width up to the overall length of the bar 30.

With reference to Figure 9 it will be noted that the copy grippers 31 are reversely bent to define a spring lip 33 extending downwardly and at the fold 34 defining a limiting surface beyond which copy may not be inserted. The limiting surface at fold 34 is so positioned that it will lie in the same horizontal plane as the limiting surface constituted by the undersurfaces of the strips 18 which are parallel to the top 16 of support 12. This arrangement is accomplished since the forward run of rod 30 rests on the top of strips 18. In this connection attention is called to Figures 3 and 4. Thus, when rod 30 is placed in operation, copy grippers 31 may have their spring lips 33 aligned with the underside of strip 18 merely by forcing the forward run of rod 30 down into

contact with the upper surface of strips 18. This eliminates chance of error since regardless of how many times rod 30 may be removed and replaced, once it is inserted in barrel 19 it is only necessary to swing bar 30 forward to point of contact with strips 18 to insure alignment of the copy grippers 31 in such a way that they will cooperate with copy gripper 17 in aligning the same edge of a piece of copy. The operation of the copy holder as a whole, when rod 30 and grippers 31 are attached, is similar to the operation heretofore described. In releasing the paper, however, it is necessary separately to release the edge from each of the grippers 31 in addition to effecting the release of bar 17. The lips of grippers 31 are opened by applying pressure to the base of the spring lip 33. It will be recognized that limiting surface 34 will be aligned with the limiting surface of L-strips 18 when the clip is in closed or gripping position as shown in Figure 9. The centrally raised portion in the forward run of rod 30 overlies the thumb piece 24 and facilitates separation of bar 17 from the copy support 12 in the insertion and removal of papers.

In operation of the copy holder the line guide 26 remains in fixed horizontal position because of its attachment to the standard 11, while the copy support 12 is raised and lowered with respect thereto. The means for adjusting the support with respect to the standard is disclosed in detail in my co-pending application Serial No. 366,463, previously acknowledged. In brief, it comprises means for advancing the copy support with respect to its standard in a step-by-step movement and to hold the support in each of its adjusted positions while text on any particular line is being copied.

Although the foregoing description has been concerned with the preferred embodiment of this invention, it will be understood that many modifications of the illustrated construction may be made within the scope of the appended claims.

What I claim is:

1. In a copy holder, a copy support, a releasable clamp coacting therewith for holding copy thereagainst, means constituting a part of said clamp for aligning copy gripped thereby, and means extending laterally of said copy support, said means including copy grippers located laterally beyond said copy support, the copy grippers also including aligning means in the same plane as the aligning means of the main clamp, whereby copy wider than said copy support may be held in aligned position thereby.

2. In a copy holder, a copy support, a releasable clamp coacting therewith for holding copy thereagainst, means constituting a part of said clamp for aligning copy gripped thereby, and detachable means extending laterally beyond said copy support, said means including copy grippers located laterally beyond said copy support, the copy grippers also including aligning means in the same plane as the aligning means of the main clamp, whereby copy wider than said copy support may be held in aligned position thereby.

3. In a copy holder, a copy support, a releasable clamp coacting therewith for holding copy thereagainst, means constituting a part of said clamp for aligning copy gripped thereby, and means detachably mounted on said clamp and extending laterally beyond the copy holder, said means including copy grippers located laterally beyond said copy support, said copy grippers in-

cluding aligning means in the same plane as the aligning means of the main clamp, whereby copy wider than said copy support may be held in aligned position thereby.

4. In a copy holder, a copy support, a main clamp coacting therewith for holding copy thereagainst, said main clamp being resiliently urged to bear against said copy support but movable to release copy held thereagainst, said main clamp including means adapted to coact with an edge of copy placed thereunder to align the latter, a member detachably mounted on said main clamp and extending laterally beyond the copy holder, and copy grippers slidably mounted on said member for lateral movement, a part of said grippers being adapted to coact with an edge of copy placed therein to align the latter, said part of said grippers being in the same horizontal plane as the means of similar function constituting a part of said main clamp, whereby copy of a width in excess of the width of said copy support may be held in aligned position.

5. In a copy holder, a copy support, a main clamp coacting therewith for holding copy thereagainst, said main clamp presenting an unbroken gripping surface extending the entire width of the copy support, said main clamp being resiliently urged to bear against said copy support but movable to release copy held thereagainst, said main clamp including means adapted to coact with an edge of copy placed thereunder to align the latter, a member detachably mounted on said main clamp and extending laterally of the copy holder, and copy grippers slidably mounted on said member for lateral movement, a part of said grippers being adapted to coact with an edge of copy placed therein to align the latter, said part of said grippers being in the same horizontal plane as the means of similar functions constituting a part of said main clamp, whereby copy of a width in excess of the width of said copy support may be held in aligned position.

6. In a copy holder, a copy support, a releasable clamp coacting therewith for holding copy thereagainst, a part of said clamp serving to align copy gripped thereby, movable means detachably mounted on said clamp and extending laterally of said copy support, copy grippers mounted on said means, said grippers each including a surface adapted to align copy placed therein, the part of the clamp serving to align copy also serving to align the movable means when it is moved into contact therewith so that the aligning surface of the grippers lies in the same horizontal plane as said part, whereby copy wider than the copy holder can be held by both the clamp and the grippers in aligned position.

7. In a copy holder, a copy support, a copy clamp having a downwardly extending jaw for coaction with the upper portion of said copy support to clamp copy therebetween and a rearwardly extending portion constituting an abutment for aligning copy by engaging the edge thereof as the same is mounted in position to be clamped, spring means normally urging the downwardly extending jaw of said clamp against said copy support, a member carried by said clamp and movable therewith to clamping and released positions, a pair of copy retaining clips adjustably mounted on said member for movement thereon, said clips being formed with abutments in alignment with the abutment of said clamping means whereby copy secured therein is positioned by reference to its upper edge in contact with such abutments.

8. In a copy holder, a copy support, a clamp comprising a downwardly extending jaw engageable with the upper portion of said copy support and a rearwardly extending portion constituting an abutment for the upper edge of the retained copy, said clamp being bodily movable to unclamping position, spring means secured to said clamp and tending normally to urge the downwardly extending jaw thereof toward the copy supporting surface, a member carried by said clamp and movable therewith to clamping and

unclamping position, said member extending laterally beyond said copy support, spring clips slidably mounted on said member for securing copy at spaced points at either end of said clamp, said clips each comprising a depending portion, a reversely bent arcuate portion and a flat downwardly extending lip opening to receive copy when said clip is compressed to flatten said arcuately curved portion.

EDWARD L. ELLIOTT.
